TEXTILE SPINNING

Harrison B. Williams, Danville, Va.

Application April 14, 1955, Serial No. 501,291

9 Claims. (Cl. 57—58.95)

The present invention relates to spinning textile fibers into yarns and includes both structural and procedural improvements in the art.

According to the present invention a regulated quantity of discrete fibers are conveyed by moving air longitudinally through a revolving tube. The revolving tube includes an inlet feed conveyor tube section, a collector section and an outlet tube section. The collector section is surrounded by a vacuum box provided with seals in which it journals the conveyor section of the tube and the outlet section of the tube. The collector section is provided with a baffle plate surrounding the outlet and opposite the inlet conveyor. It is also provided with a plurality of circumferential apertures positioned adjacent the edges of the baffle plate. These apertures place the spinning tube in communication with the vacuum and then form what may be termed a collecting screen for trapping moving fibers. The collected fibers are continuously withdrawn through the outlet section of the tube and twisted into the yarn by take-up means which package the newly formed yarn. Twisting is caused by the rotation of the tube and collector with respect to the take-up. The annular face of the collector screen may be provided with a plurality of small burrs which tend to maintain the position of the fibers as they are withdrawn during yarn formation. This assists in paralleling the fibers and making the twisting action more positive.

The gist of this invention is the discovery that individual fibers may be collected from an air stream by impinging them on an apertured surface and that the thus collected fibers may be formed into a yarn by continuously withdrawing them while relative rotation is maintained between the take-up and the collecting surface.

Several models of the present invention have been constructed and have successfully spun yarns of controlled size and controlled twist. In each of the models made and tested, the apparatus was constructed to provide a rotating spinning tube, a feed for the tube, a take-up assembly and a vacuum surrounding and in operative relationship with the collecting section of the tube. Obviously, any means for feeding regulated quantities of individual fibers to the tube will be satisfactory for purposes of this invention, but it has been found expedient to use roving as a starting material. In the models referred to above, the roving has been fed at a regulated rate of speed to a roll provided with card clothing for spacing the fibers so that they may be doffed as discrete fibers by the air moving into the feed end of the spinning tube. The take-up assembly for these models includes a take-up roll positively driven at a constant predetermined speed and a winding spindle driven frictionally by the surface of the take-up roll. Obviously, there are many other take-up means known in the art which can be adapted to use with the present invention. It will also be obvious to those skilled in the art that the take-up means may be rotated while the collection tube is held stationary. The size of the yarn produced according to this invention can be controlled by varying the ratio of

2

feed to take-up and the twist can be controlled by varying the speed at which the spinning tube is rotated in relation to the speed of the take-up.

The invention will be better understood by reference to the accompanying drawings in which

Fig. 1 is a perspective view of a preferred form of the invention omitting the motor and part of the driving belts for purposes of clarity;

Fig. 2 is a diagrammatic representation of the feed, the spinning tube without the vacuum box and the take-up;

Fig. 3 is a cross-sectional view of a spinning tube and vacuum box illustrating operation of the invention;

Fig. 4 is a partial section showing the collector of the spinning tube with the burrs enlarged for purposes of illustration; and

Fig. 5 is a cross-sectional view of another modification of the spinning tube.

The preferred form of the invention shown in Figs. 1 to 4 includes a frame 8 which mounts a spinning tube assembly indicated generally at 10, a feed assembly indicated generally at 12, a take-up assembly indicated generally at 14 and driving means not shown.

The feed assembly includes a supply bobbin of roving 16, a feed roll 20, a feed plate 26 and a second feed roll 30. Feed roll 20 is fixed on a shaft 22 driven by pulley 24 and belt 25. Feed plate 26 is provided with a hole 28 and it is mounted on frame 8 so that it cooperates with roll 20 in advancing roving to roll 30. Roll 30, covered with card clothing 32, is fixed on a shaft 34 driven by pulley 36 and belt 40. In operation the speed of cylinder 30 may be constant while the speed of feed roll 20 is varied from time to time with respect to the take-up speed to control the size of the yarn being spun. The card clothing 32 separates the fibers and presents them to the spinning tube in an accessible form for easy removal by the moving air. In commercial production, a plurality of spinning tubes constructed in accordance with this invention may be fed from a single card such as is commonly used in the cotton textile industry.

The spinning tube assembly 10 (Fig. 3) includes a feed tube 42, a vacuum box 44, a collector 46, a delivery tube 48 and a source of vacuum not shown. The feed tube 42 is rotatable with the collector 46 and the delivery tube 48 all of which are coaxially mounted in bearings 50 and 52 mounted on frame 8, and driven by pulley 54 and belt 56. It is not necessary that either the feed tube or the delivery tube be rotated but the collecting surface of the collector must be rotated with respect to the take-up and the common-rotation construction illustrated in the drawings is a convenient one for inexpensively accomplishing this desired result. The feed tube illustrated in Figs. 1 to 4 is 7½ inches long and has an inside diameter of ¾ inch.

The collector 46 is in the form of a cylinder which includes a solid portion 58, an outer wall 60 and one end formed as a baffle 62. It will be noted that baffle 62 extends transversely of the air conveyor feed tube 42 and that outer wall 60 is provided with a plurality of circumferential apertures 64 positioned in close proximity to the edges of the baffle 62. These apertures form, in effect, a collector screen and at their edges they are provided with a plurality of small burrs 66 for the purpose of assisting the fibers in rotating with the collector. A delivery port or ring 68 is provided in the central portion of baffle 62 and delivery tube 48 extends outward axially from the collector. The inside diameter of the collector is 1⅓ inches, the inside diameter of the delivery tube is ¼ inch and there are fifty 1/16 inch apertures around the circumference of outer wall 60. The distance from the mouth of the feed tube to the collector plate is about ¾ inch. These dimensions do not appear to be critical but they

do represent one good operative means for carrying out this invention.

The take-up assembly includes take-up roll 70 positively driven by pulley 72 and belt 74, a wind up roll 76 mounted for movement away from roll 70 which drives it frictionally as the yarn builds up thereon.

In the driving sequence a motor not shown is mounted on the frame for driving pulley 54 through belt 56. Pulley 54 rotates the spinning tube at a speed predetermined by the pulley sizes and it also drives idler shaft 76 by means of belt 78 and pulley 80. This idler carries pulley 82 for driving shaft 34, roll 30 and pulley 84 by means of belt 40 and pulley 36. Pulley 84 drives belt 74 and pulley 72 for operating the take-up through roll 70. Roll 70 also mounts a pulley not shown and this pulley drives belt 86 which, in turn, drives idler shaft 88 through pulley 90. Shaft 88 also carries pulley 92 which drives feed roll 20 by means of belt 25 and pulley 24. Speed changes and relative speed variations are accomplished by using pulleys of different diameters. It will be obvious to one skilled in the art that these same results can be achieved by means of gears or other mechanical arrangements commonly used for such purposes.

In operation, a source of vacuum is first placed in communication with vacuum box 44 and a piece of spun yarn 94 is fed into delivery tube 48 under the influence of the vacuum. At the same time, the end of roving from supply bobbin 16 is led through hole 28 of the feed plate 26 and under feed roll 20 where it will be trapped between the end of plate 26 and the card clothing 32. The motor is then started and the fibers are continuously pulled out of the roving by the card clothing from which they are removed by the air blast entering the feed end of feed tube 42. In Fig. 3, the fibers are shown moving towards the apertures 64 in collector 46. Some of the collected fibers attach themselves to the piece of spun yarn 94 and the operation proceeds smoothly. Just the mere withdrawal of the spinning yarn will clear the collector continuously and the twist imparted by the relative rotation of the collector and the take-up imparts strength to the yarn. The role of the burrs 66 is not completely clear, but it has been clearly established that they do assist in making a better yarn, particularly in terms of uniformity.

The modified spinning tube shown in Fig. 5 includes a feed tube 142, a delivery tube 148 and a collector 146 provided with a plurality of apertures 164. It operates in exactly the same manner as the tube shown in Fig. 3 although the yarn it spins is not of as high quality as that of the preferred form of the invention. Other modifications have been tested and found satisfactory. In one of the more successful of these, the holes 64 are bored at about a 45° angle from the delivery end of the collector inward towards the axis. This also appeared to facilitate the formation of burrs 66.

Other modifications will be obvious to those skilled in the art.

I claim:

1. A device for spinning textile fibers comprising a rotating spinning tube having a feed end and a delivery

end driven at a predetermined speed, said tube having a plurality of apertures intermediate its ends forming a collecting surface therein, a source of vacuum surrounding said tube at said apertures, means for feeding individual fibers to the feed end of said tube and take-up means for withdrawing yarn from the delivery end of said tube, said take-up means being fixed with respect to the rotation of the spinning tube, whereby twisting is effected.

2. A device as set forth in claim 1 wherein said collecting surface is provided with means for holding the fibers on said surface in generally the same relationship in which they are collected thereon.

3. A device as set forth in claim 1 wherein the feed end of said tube has a larger inside diameter than the delivery end.

4. A textile yarn spinning apparatus comprising a spinning tube including a feed tube, a coaxial baffle provided with a central delivery port and an air escape means adjacent the outer surface of the baffle for forming a collector, a source of vacuum for continuously withdrawing air through said air escape means and establishing an air conveying system in said feed tube, means for rotating said spinning tube at a predetermined speed, means for supplying fibers to the spinning tube at a predetermined rate, and yarn take-up means for withdrawing said fibers from said delivery port at a predetermined rate, said last named means being fixed with respect to the rotation of said spinning tube, whereby twisting is effected.

5. A device as set forth in claim 4 wherein the baffle is a round plate extending across the spinning tube, a plurality of small projections are positioned adjacent the air escape means, the air escape means is a plurality of small apertures spaced circumferentially about the wall of the spinning tube on the feed tube side of the baffle and in close proximity thereto, and the feed tube is of a larger diameter than the delivery port.

6. A device as set forth in claim 5 wherein the baffle has a radius between the length of the fibers being spun and one-half the length of the fibers being spun and the delivery tube has a length equal to more than three times the length of the fiber being spun.

7. A device as set forth in claim 6 wherein the diameter of the feed tube is less than one-half the diameter of the baffle.

8. A device as set forth in claim 7 wherein the delivery port is provided with a delivery tube extending axially towards the take-up means.

9. A device as set forth in claim 8 wherein the feed tube mounts the bearings and drive means for rotating the spinning tube.
